US0D1064761S

(12) **United States Design Patent** (10) **Patent No.:** **US D1,064,761 S**
(45) **Date of Patent:** **** Mar. 4, 2025**

(54) **CRIMPING TOOL**

- (71) Applicant: **Crimpit Group Ltd**, London (GB)
- (72) Inventors: **Ian Peter Critchlow**, Warrington (GB); **Michael David Harper**, Warrington (GB)
- (73) Assignee: **Crimpit Group Ltd**, London (GB)
- (**) Term: **15 Years**
- (21) Appl. No.: **29/951,366**
- (22) Filed: **Jul. 9, 2024**

Related U.S. Application Data

- (63) Continuation of application No. 29/906,092, filed on Oct. 31, 2023, now Pat. No. Des. 1,036,206.

(30) **Foreign Application Priority Data**

Jun. 1, 2023 (GB) 2308203
Jun. 9, 2023 (GB) 6288993

CLAIM

The ornamental design for a crimping tool as shown and described.

DESCRIPTION

FIG. 1 is a first perspective view of our design; FIG. 2 is a front view of our design; FIG. 3 is a rear view of our design; FIG. 4 is a top view of our design; FIG. 5 is a bottom view of our design; FIG. 6 is a right side view of our design; FIG. 7 is a left side view of our design; FIG. 8 is a second perspective view of our design, showing the crimping tool partially open; and, FIG. 9 is a third perspective view of our design, showing the crimping tool fully open. The broken lines depict portions of the crimping tool that form no part of the claim. The long-short dashed lines represent surface boundaries and form no part of the claimed design.

1 Claim, 7 Drawing Sheets
